BLANK ALIGNING MECHANISM AND
METHOD

Abraham Novick, Flushing, N. Y., assignor to
F. L. Smithe Machine Co., Inc., New York, N. Y.,
a corporation of New York

Application October 7, 1931, Serial No. 567,372

9 Claims. (Cl. 271—50)

The present invention relates to improvements in mechanism for aligning blanks. In machines for making envelopes from envelope blanks it is necessary in feeding the blanks to the folding mechanism to convey them in sequence, one after the other, in such a manner that each blank is completely free of its fellows. In some instances the blanks are previously gummed and dried while in a band which is formed by the overlapping of one blank by the other, whereupon it becomes necessary to separate or individualize the blanks and then to properly align them with respect to the operating mechanism in order that they may be in correct register with the mechanism accomplishing the subsequent folding operations. In previous devices it has been customary to separate the blanks from the band and then align the blanks by interrupting the motion of the blanks at regular intervals while such blanks are on the conveyor, or otherwise to retard the movement of the blanks through the machine.

The present invention aims to align the blanks and place them in correct registry in the machine, without, however, retarding the movement of the blanks, thus making for an increased output per machine. While it is usually necessary to align the blanks immediately following the individualizing operation, the mechanism described may, of course, be used at any point in the envelope making machine where it is desired to align or bring them into registry with the machine.

In accordance with the present embodiment of the invention, each blank after having been separated from the stack or band by an individualizing device is placed upon a conveyor or conveying element which preferably has a linear speed somewhat faster than such device, the blanks being constrained to have the movement of the conveyor by means of an element supplying the necessary pressure upon the blank against such conveyor. While the blank is thus travelling on the conveyor, it is acted upon by a further conveying element which travels at a greater speed than the blank to push it from behind and thereby to accomplish the correct registry of the blank with reference to the machine.

The invention will be best understood from the following description taken with the annexed drawing, in which

Figure 1 is a view in side elevation of a preferred embodiment, while Figure 2 is a plan view of a part of the mechanism shown in Figure 1.

Referring now to the drawing in greater detail, the blanks 10 are shown within a hopper 11, the blanks being formed in a band such that each blank overlaps the next, and in the particular instance shown the blanks have just emerged from a drying way. The blanks are fed from

this band one by one by means of rotating wheel 13 which has mounted on it grippers 15, 16, the action of this element being such that as it rotates, the grippers 15, 16 contact with the top-most sheet of the blanks and feed it on individually. Co-acting with the grippers 15, 16 is a pivoted, resiliently mounted counter-element 17 of bellcrank shape, said element being spring pressed against the portion of the sheet opposite the wheel 13 as shown. The blank, which has thus been individualized, falls upon the conveyor 20 and is held on it by means of the roller 21 which preferably is journaled in a pair of brackets 23 which are pressed downwardly in a direction against the blank by means of a spring 25. The tension of spring 25, however, is such that the roller bears only lightly on the blank so that the blank is free to assume any position required by the aligning element, to be described. The pressure of the roller 21 against the blanks is sustained by a table 20a.

Said aligning element comprises preferably a pair of chains 27 on either side of the conveyor 20 having thereon pins 28, said chains being driven by sprocket wheels 31, 31, 31, 31. It will be noted that the brackets 23 are pivotally held in a clamp member 24 which is adjustably held upon a longitudinal member 24a.

In the operation of the mechanism, the blank having been fed out upon the conveyor 20 passes between that conveyor and roller 21 which causes it to have the motion of that conveyor. It is then acted upon by the pins 28 of the chains 27, 27, which move at a somewhat faster speed than the conveyor 20, and thus enable the pins to overtake the blank, and, aided by the roller 21, effectively register the blank on the conveyor, this action being shown in Figure 2. The blank is now ready for the folding mechanism, the scoring elements 35, 35 of which are seen in Figure 1. Roller 21 bears on the blank just lightly enough to cause it to have the motion of the conveyor without preventing the movement of adjustment of the blank caused by the action of the pins 28.

I have described what I believe to be the best embodiment of my invention. I do not wish, however, to be confined to the embodiment shown, but what I desire to cover by Letters Patent is set forth in the appended claims.

I claim:

1. In an envelope making machine, mechanism for aligning blanks comprising a relatively slow-moving conveyor, means for feeding said blanks upon the conveyor in separated condition, a contact element pressing the blanks at a medial region thereof yieldingly against the conveyor so as to cause them to assume the movement of the conveyor but also allowing for movement of adjustment of the blanks with reference to the

conveyor, and secondary conveyor mechanism adapted to move in juxtaposition to, and at a faster speed than, the conveyor first mentioned and having thereon blank engaging means adapted to engage the blank at opposite sides of said medial region and to push the blank from behind and, aided by the contact element, to effect an alignment of the blanks.

2. In an envelope making machine, mechanism for aligning blanks comprising a conveyor, means for feeding said blanks upon the conveyor in separated condition, a contact element pressing the blanks against the conveyor so as to cause them to assume the movement of the conveyor but also allowing for movement of adjustment of the blanks with reference to the conveyor, and a second conveyor adapted to move at a faster speed than the conveyor first mentioned comprising a pair of conveying elements on either side of the conveyor first mentioned, said conveying elements having thereon blank engaging elements which push the blanks from behind and, aided by the contact element, effect an alignment of the blanks.

3. In an envelope making machine, mechanism for individualizing and aligning envelope blanks comprising an individualizing device proper by means of which the blanks are separated from a collated condition, a relatively slow-moving conveyor upon which said blanks are fed by the individualizing device, a contact element pressing the blanks at a medial region thereof yieldingly against the conveyor so as to cause them to assume the movement of the conveyor but also allowing for movement of adjustment of the blanks with reference to the conveyor, and secondary conveyor mechanism adapted to operate at a faster speed in juxtaposition to said slower-moving conveyor, and having thereon means for engaging the blank at opposite sides of said medial region and for pushing the blank from behind, to act, in cooperation with said contact element, to align the blank.

4. The method of aligning blanks having wedge shaped flaps which consists in feeding the blanks upon a travelling conveyor in separated condition, with said flaps trailing, moving said conveyor at a speed at least equal to the rate of feed of the blanks to said conveyor and then aligning the blanks while on said conveyor by engaging them at a reentrant corner at each side thereof, and pushing them from behind by aligning elements moving at a higher speed than said conveyor engaging the corners formed by the said flaps and the bodies of the blanks.

5. The method of aligning blanks having wedge shaped flaps which consists in feeding the blanks upon a conveyor in separated condition, with said flaps trailing, moving said conveyor at a speed at least equal to the rate of feed of the blanks to said conveyor and then aligning the blanks while on said conveyor by pushing them from behind by aligning elements moving at a slightly faster speed than said conveyor and engaging the corners formed between said flaps and the bodies of the blanks, while loosely constraining the blanks, by yielding pressure against a medial region thereof, to move with said conveyor.

6. In an envelope making machine of the class comprising a mechanism for operating on individual blanks having wedge shaped flaps, means for conveying a series of blanks in overlapped

formation with said flaps trailing, and an individualizing mechanism for removing blanks from said overlapped formation so that said blanks may be passed individually into and through said operating mechanism, the combination therewith of means for conveying said blanks from said individualizing mechanism to said operating mechanism, said means including a conveying device engaging said blanks from behind in the corners formed between said wedge shaped flaps and the bodies of the blanks to effect alignment thereof and deliver them so aligned into the operating mechanism.

7. In an envelope making machine, characterized by mechanism for operating on individual blanks having flaps forming re-entrant corners with the bodies of the blanks, a conveyor for conveying a series of blanks in overlapped formation with said flaps trailing, an individualizing mechanism for removing single blanks from said overlapped formation, said mechanism comprising a rotating wheel having mounted thereon elements for gripping the uppermost of the sheets arriving at the said wheel and pulling said sheet at increased speed out of said overlapped formation, a counter-element mounted adjacent said wheel and cooperating therewith for restraining blanks under the said uppermost sheet from following said sheet in its movement in response to said gripping elements, and aligning mechanism for engaging said blanks at each side at said re-entrant corners, thus aligning them while conveying the individualized blanks into said operating mechanism.

8. In an envelope making machine, mechanism for aligning blanks comprising a relatively slow-moving conveyor, means for feeding said blanks upon the conveyor in separated condition, a contact element pressing the blanks at a medial region thereof yieldingly against the conveyor so as to cause them to assume the movement of the conveyor but also allowing for movement of adjustment of the blanks with reference to the conveyor, and relatively faster-moving secondary conveyor mechanisms, one on either side of, and in juxtaposition to, said first-mentioned conveyor, having thereon blank-engaging means adapted to push the blank from behind and effecting an alignment of the blanks, aided by the contact element.

9. In an envelope making machine, mechanism for individualizing and aligning envelope blanks comprising an individualizing device proper by means of which the blanks are separated from a collated condition, a relatively slow-moving conveyor upon which said blanks are fed by the individualizing device, a contact element pressing the blanks at a medial region thereof yieldingly against the conveyor so as to cause them to assume the movement of the conveyor but also allowing for movement of adjustment of the blanks with reference to the conveyor, and secondary conveyor mechanisms adapted to operate at a faster speed in juxtaposition to said slower-moving conveyor, one at either side thereof, and having thereon blank-engaging means adapted to push the blank from behind, and which effect an alignment of the blanks, aided by the contact element.
